Attorney.

UNITED STATES PATENT OFFICE

ERNEST SANDERS, OF DETROIT, MICHIGAN

SHOW CASE

Application filed November 21, 1930. Serial No. 497,203.

The invention relates to improvements in display cases and more particularly to an improved means for effectively illuminating refrigerated display cases by artificial lighting means arranged outside of the case.

An object of the invention is to provide improved means for illuminating refrigerated display cases without impairing the efficiency of the refrigerator.

10 Another object is to provide an improved structure wherein artificial lighting means is mounted on the exterior of a refrigerated display case and concealed without subjecting any portion of the display case to overheating.

Another object is to provide means to conceal artificial lighting means on display cases without impairing the efficiency of the illuminating system.

20 Another object is to provide means to prevent overheating of the artificial illuminating means.

Another object is to provide a refrigerated display case with improved inexpensive and effective means for cooling, shielding, and protecting artificial illuminating means.

The foregoing and such other objects of the invention as will appear hereinafter as the description proceeds, will be more readily understood from a perusal of the following specification, reference being had to the accompanying drawings, in which:

Fig. 1 is a fragmentary perspective view of the improved display case.

35 Fig. 2 is a transverse sectional view through the upper portion of the display case.

It is obvious that artificial illuminating means cannot satisfactorily be placed within a refrigerated display case because the heat created by such illuminating means defeats the efficiency of refrigeration. Arrangement of artificial illuminating means on the outside of a display case necessitates the employment of shields and reflectors, or similar devices, to direct the light into the interior of the case. Such shields, reflectors, or the like, often detract from the appearance of the display case and become overheated, and may cause discomfort or injury, by burn-

ing, to persons inspecting the contents of the display case.

The improved construction is such that the artificial illuminating means, although mounted on the exterior of the display case, 55 is completely concealed by the construction of said case, and is provided with means to protect the lighting means against overheating, which usually results in the lighting means burning out, and to prevent overheating of the exterior of the case.

As illustrated in the accompanying drawings, a conventional form of refrigerated display case is shown comprising like end walls 11 and a vertical front wall 12. Cases of this character usually are substantially rectangular in plan, and are provided with an inclined transparent front panel 13 which extends upwardly from the front wall 12 and is mounted at its upper edge in a suitable substantially narrow frame structure 14. The frame structure 14, defining the upper portion of the case preferably is built up, as illustrated in Fig. 2, of several layers of material 15 having suitable insulating material, such as for example, hair, or fiber 16 arranged between said layers. The usual closure doors 17 are provided on the rear side of the display case, whereby access may be had to the interior.

A substantially rectangular sheet metal panel 18 forms a top for the upper end of the display case, said panel having depending marginal flanges 19 therearound for embracing the frame structure 14 to provide a finished appearance to the display case.

It will be noted, upon reference to Fig. 2, that the upper edge of the inclined transparent front panel 13 is supported in the frame structure 14 inwardly of the front marginal flange 19' of the panel 18. This manner of supporting the transparent panel 13 provides sufficient space between said transparent panel and the marginal flange 19' to receive any number of light fixtures 21. 85 These fixtures are of any approved type adapted to receive artificial lighting means preferably in the form of conventional electric light bulbs 22. The marginal flange 19' on the forwardly extending edge of the top 100

panel 18 is offset longitudinally to provide an outwardly downwardly extending shoulder portion 23, which shields the artificial lighting means 22 from view without completely enclosing said lighting means to cause its being overheated and subsequently burned out. The improved structure insures free circulation of air about the artificial lighting means 22. A plurality of holes 24 are provided in the flange 19 adjacent each light fixture to increase the circulation of air about each light source.

It can readily be understood that the improved mounting for the artificial lighting means on the outside of a refrigerated display case prevents overheating of said case and overheating of the top 18.

Although an exemplary form of the improved refrigerated display case is illustrated in the accompanying drawings and described in detail in the foregoing specification, it is to be understood that the improved structure may embody certain modifications in detail structure falling within the spirit of the invention and the scope of the appended claims.

I claim:

1. A top, for a display case, comprising, in combination, a substantially rectangular sheet of material having downwardly extending marginal flanges on its edges, one of the longitudinal flanges being spaced from the display case and having a longitudinal offset extending outwardly downwardly to shield artificial lighting means mounted on the upper end of the display case, and said one flange having a plurality of openings therein adjacent each lighting means to effect circulation of air around said lighting means.

2. A top for a display case comprising a substantially rectangular sheet of material having a flange extending therefrom around its edges, the flange on one side of said sheet being spaced from the side of said display case and extending outwardly downwardly over its entire length, said flange having its marginal edge turned downwardly substantially parallel with the flanges to provide a reflector for lighting means arranged on said display case below said top.

50. In testimony whereof I affix my signature at Detroit, Michigan.

ERNEST SANDERS.
